(57) **CLAIM**

The ornamental design for a TV receiver, as shown and described.

DESCRIPTION

1. TV receiver

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

The broken lines shown in figures 1.7 and 1.14 depict unclaimed portions of the TV receiver and form no part of the claimed design.

The subject TV receiver design is made in a way that the stand can be moved to the left or to the right; the reproductions 1.1 to 1.7 show the state prior to the change and the reproductions 1.8 to 1.14 after the change, where the stand is moved inwards.

1 Claim, 12 Drawing Sheets(58) **Field of Classification Search**
